(57) **CLAIM**

The ornamental design for a brake handle, as shown and described.

DESCRIPTION

FIG. 1 is a front, left, isometric view of a brake handle in accordance with the present design shown in a closed configuration.

FIG. 2 is a left side elevation view thereof.

FIG. 3 is a right side elevation view thereof.

FIG. 4 is a top plan view thereof.

FIG. 5 is a bottom plan view thereof.

FIG. 6 is a front elevation view thereof.

FIG. 7 is a rear elevation view thereof.

FIG. 8 is a front, left, isometric view of the brake handle of FIG. 1 with a feature of the brake handle shown in an open configuration; and,

FIG. 9 is a front, left, isometric view of the brake handle of FIG. 1 shown in an open configuration.

The dash-dash broken lines illustrate portions of the brake handle that form no part of the claim. The dot-dash broken lines depict a boundary between claimed and unclaimed portions of the brake handle and form no part of the claimed design.
